SWITCH STRUCTURE

James E. Wheeler, 2256 Kent Blvd. NE.,
Grand Rapids, Mich.Original application Oct. 21, 1957, Ser. No. 691,404, now
Patent No. 2,964,144, dated Dec. 13, 1960. Divided
and this application Feb. 15, 1960, Ser. No. 8,698
8 Claims. (Cl. 200—61.41)

This invention relates to switching systems and more particularly to switch structure for use in interrupting the flow of current to a prime mover which controls the spatial position of a movable component. This application is a division of my application Serial No. 691,404, filed on October 21, 1957, and entitled "Airplane hangar," now Patent #2,964,144.

Accordingly therefore, a primary object of this invention is to disclose switching means for selectively interrupting the flow of current to a prime mover.

Another object of this invention is to teach structure for selectively controlling current flow in correlation with the spatial position of a movable component.

A further object of the present invention is to provide switching means for selectively regulating the period during which electrical current is allowed to flow in a given circuit.

These and other objects and advantages of the present invention will become apparent by referring to the accompanying detailed description and drawings in which:

FIGURE 1 illustrates a sectional view of the switch mechanism provided by the invention.

FIGURE 2 shows a sectional view of the switch shown in FIGURE 1 taken along the lines 2—2 in FIGURE 1.

Turning now to the drawings, reference will be made FIGURE 1 in which there is provided an illustration of the structural details of the positioning switch provided by the present invention. It will be appreciated in connection with this figure that electric current may be caused to energize an electric power unit (not shown) by means of conventional manually operable switching circuitry. The electric power unit may comprise a prime mover which causes a rotatable floor 10 for a circular aircraft hanger or like structure to revolve, and the control current for interrupting energization of power unit is regulated by the switch structure shown in FIGURE 1 and FIGURE 2. The rotatable floor 10 revolves to a position in which the flow of current is automatically interrupted by the invention with any chosen aircraft positioned for ready egress or ingress. The automatic interruption of the electric current is accomplished by the positioning switch shown in FIGURE 1. This switch includes a metallic housing 50 which may be embedded in the approach ramp to the hanger or like structure. The housing 50 is equipped with a cover plate 51 which is mounted flush with the grade level of the approach ramp by means of suitable screws 52. Within the interior of the housing 50, there is provided a pair of actuating rods 53 and 54, respectively. Each of the rods 53, 54 is provided with a roller member in the outermost extremity thereof. Thus, the roller 55 is mounted in the rod 53 and the roller 56 is mounted in the rod 54.

The rod 53 is mounted for slidable movement with respect to the vertical end wall of the housing 50. In addition, the rod 53 is resiliently biased by means of a compression spring 57 which is located between a fixed partition plate 58 and an annular shoulder 59 which is secured to the rod 53. The rod 53 is movably secured to the rod 54 by means of the swivel element 60.

In order to form one contact of the make and break portion of the positioning switch, there is provided an annular metallic disc 61 which is securely affixed to the rod 53. The disc 61 is, of course, insulated from the rod

2

53 by suitable means, and is provided with a suitable electrical conductor (not shown) which is secured thereto by means of terminal screw 61A. The opposite contact of the make and break portion takes the form of a resilient spring contact 62 which is also provided with a suitable conductor (not shown). It will be immediately obvious that linear movement by the rod 53 can make or break the conductive contact between the disc 61, and the spring contact 62.

Thus, if the linear movement of the rod 53 can be caused to occur when the rotatable floor reaches a certain predetermined position, the movement of the floor and the airplanes thereon can be correlated with respect to the position of the closure for the hangar.

10 15 This linear movement of rod 53 is effected by engagement with one of the deflecting members 63, as shown most clearly in FIGURE 2. It will be appreciated from an inspection of FIGURE 2 that when one of the deflecting members 63 is rotated far enough, it is able to deflect 20 the roller 55 and cause a separation between the disc 61 and the spring contact 62. It should be appreciated in this connection that the radially spaced deflecting members 63 may be used when a number of aircraft are housed within a structure having a rotatable floor.

25 30 For example, it is possible to house five aircraft within such a hangar structure. Under these circumstances, the automatic interruption of energizing current for drive unit 31 is effected by the rod 54 and its associated components. In order to accomplish five aircraft operation, the cover plate 51 may be removed from the metallic housing 50. Then, a suitable elongated member is inserted through the hole 64 located in tab 65 which comprises a flattened extension of the rod 53. When the tab 65 has been rearwardly retracted in order to compress 35 the spring 57, it is rotated 90° in order to lock the rod 53 in retracted position. It should be appreciated that the tab 65 is normally centered for movement within an elongated slot 66 which is provided in the fixed partition plate 58A.

40 45 After the actuating rod 53 has been retracted, the lower actuating rod 54 is readied for operation. This is accomplished by rotating tab 67 on rod 54 through 90°, in order to position the rod 54 for slidable movement. This action has the effect of releasing rod 54 from its retracted position, and places roller 56 in position for

actuation by any one of the deflecting members 68. The deflecting members 68 are radially spaced around the outer rim of the floor 10, and are vertically spaced somewhat below the earlier mentioned set of deflecting members 63.

50 55 It will be observed in FIGURE 1 that the actuating rod 54 is equipped with a compression spring 69 which is positioned between the fixed partition plate 58 and an annular shoulder 70 located on the rod 54. The make and break portion of the positioning switch in this instance again takes the form of two contacts. One of these contacts is formed by the annular metallic disc 71 which is secured upon and insulated from the rod 54. The opposite contact is, of course, the spring contact 62.

55 60 During the intervals when five aircraft are housed within the structure, as explained immediately above, rotation of the floor 10 may be initiated by effecting a flow of electric current to a conventional power unit or prime mover. Then, rotation of the floor 10 continues until one of the deflecting members 68 engages the roller 56 mounted in the end of rod 54. This, of course, has the effect of displacing the annular metallic disc 71 on rod 54 out of engagement with the resilient spring contact 62. As a result, the flow of current to the drive unit is selectively interrupted when any or each of the aircraft is centrally positioned for ingress or egress with respect to the closure for the hangar structure.

65 70 75 Although the present invention has been described in

connection with aircraft housing structures, it will be appreciated that the switching mechanism may be employed equally well in connection with many other applications, and that such use would be deemed to fall within the purview of the appended claims.

What I claim is:

1. In a switch mechanism for selectively interrupting a flow of electric current by breaking an electrical contact in correlation with the spatial position of a member driven by a power unit, housing means, rod means disposed for slidable motion within said housing means, and projection means on said driven member for contacting said rod means when said member assumes a predetermined spatial position to impart slidable motion to said rod means and thereby break said electrical contact.

2. In a switch mechanism for selectively interrupting a flow of electric current by breaking an electrical contact in correlation with the spatial position of a member driven by a power unit, housing means, rod means disposed for slidable motion within said housing means, resilient biasing means disposed to urge said rod means toward a position against said member, and projection means on said member for contacting said rod means when said member assumes a predetermined spatial position to move said rod means in a direction opposite that in which it is urged by said biasing means and thereby break said electrical contact.

3. In a switch mechanism for selectively interrupting a flow of electric current by breaking an electrical contact in correlation with the spatial position of a member driven by a power unit, housing means, rod means disposed for slidable motion within said housing means, projection means on said member for contacting said rod means when said member assumes a predetermined spatial position to impart slidable motion to said rod means and thereby break said electrical contact, and perforated tab means carried by said rod means on its end remote from said member for selectively retaining said rod means in a position out of contact with said member.

4. In a multi-circuit positioning switch for interrupting the supply of current to a drive means, housing means, a pair of resiliently biased actuator rods slidably disposed within said housing means, said rods including tab means for selectively locking one or the other thereof in inoperative position, a movable member driven by said drive means, said movable member defining at least one projection adapted to contact each of said actuator rods when said movable member assumes a predetermined spatial position and thereby impart slidable motion to the con-

tacted actuator rod and condition responsive contact means operatively associated with each of said rods for effecting said interruption of said current when said slideable motion is imparted to the contacted rod by said projection means.

5. In a multi-circuit positioning switch for interrupting the supply of current to a drive means, a plurality of resiliently biased selectively retractable rod means, swivel means interconnecting said rod means, a movable member driven by said drive means, said movable member defining a plurality of projections, each adapted to contact one of said retractable rod means when said movable member is in a predetermined spatial position and thereby impart slidable motion to the contacted retractable rod means, and contact means mounted upon said rod means to break the particular circuit governed by the position of said contacted retractable rod means.

6. In a switch mechanism for selectively opening an electrical circuit in correlation with the spatial position of a movable member having a surface adapted to move past a sensing location, a rod normally adapted to contact said surface, electrical contact means carried by said rod for completing said electrical circuit, projection means located on a predetermined portion of said surface adapted to contact said rod when said movable member assumes a position in which said predetermined portion of said surface is adjacent said rod and move said rod away from said surface, thereby causing said electrical contact means to open said electrical circuit.

7. In a switch mechanism for selectively opening an electrical circuit in correlation with the angular position of a rotatable member, rod means normally adapted to contact a surface of said rotatable member, electrical contact means carried by said rod means for completing said electrical circuit, projection means located on a predetermined portion of said surface adapted to contact said rod means when said rotatable member assumes a predetermined angular position in which said predetermined portion of said surface is adjacent said rod means and move said rod means away from said surface, thereby causing said electrical contact means to open said electrical circuit.

8. A switch mechanism according to claim 7 wherein said rotatable member comprises a circular floor of an aircraft hangar.
